April 23, 1935.

H. H. CAMERON

1,999,085

ADVERTISING DEVICE OR NOVELTY

Filed Aug. 17, 1934

INVENTOR
H. H. CAMERON

UNITED STATES PATENT OFFICE

1,999,085

ADVERTISING DEVICE OR NOVELTY

Herbert H. Cameron, Cleveland, Ohio

Application August 17, 1934, Serial No. 740,330

2 Claims. (Cl. 40—2)

The object of this invention has been to produce a simple and meritorious advertising novelty or device primarily useful in connection with competitions or contests instituted by advertisers for creating sales interest in their products, or for keeping the names of advertisers constantly before the public.

Another object of the invention has been to so design the advertising novelty or device as to lend 10 an element of mystery or secrecy to certain indicia which is applied thereto and which must be consulted and used in conjunction with the contest or competition for which the advertising novelty is employed. Describing the invention somewhat 15 more specifically, in its preferred form, I avail of a common type of match holder such as well known today for use in supplying paper matches, such a match holder lending itself very excellently to the application thereto of advertising 20 data which advertises the person or concern putting out the match holder to the public. I locate in certain space between the match carrying tabs and the back of the cover portion of the holder, the normally secret or hidden indicia 25 which is to be used for the contest purposes, and this indicia preferably takes the form of a series of letters of the alphabet or it may comprise numbers or other characters of a similar nature. The indicia is maintained hidden normally when 30 the match holder is dispensed to the user by being located at a portion of the cover member for the matches intermediate the match carrying flap and the back of the cover portion, and is kept hidden by means of the staple or fastening member that attaches the match carrying tabs to the said carrying flap and back of the cover member.

Now in the use of my invention I contemplate that the manufacturer or producer of the goods, 40 or other person or concern utilizing my advertising novelty shall establish a contest or competition. Preferably this competition may take the form of a competitive jingle contest wherein the person receiving the match holder is required by 45 the rules of the contest to write a jingle or limerick, say of two lines, using the letters printed in the match holder or equivalent article at the normally hidden or closed portion thereof which is clamped closed by the staple above referred 50 to. The conductor of the contest, namely the advertiser, will offer a prize or prizes for the best jingle produced by using the letters or indicia found in the match holder. Since this indicia is not accessible when the receiver obtains the same 55 from the store, restaurant, cigar counter, or other place from which the holders will be given out, he does not know when he asks for one of these match holders what letters comprise the hidden indicia of the article, but after the article is in his possession he will tear the back of the cover portion away from the match holding flap and this will expose to view the said indicia, whereupon he may avail thereof for the purpose of writing his jingle or jingles to submit in the contest.

Now an especial object of the invention has 10 been to so construct or form the back of the cover member of the match holder as to readily permit of this back being torn away from the match holding tabs in such a manner that the letters comprising the indicia for writing the jingle will 15 be fully exposed to view.

Of course the user of the article dispensed, which in this instance is a match holder, will be required to furnish at the time he sends in the jingle or limerick in the contest referred to, the 20 empty match holder or holders from which he has obtained the letters that are used by him in writing his jingle or limerick. Under these conditions, it is obvious that the person who enters the contest and who employs the useful match 25 holder or article of manufacture constituting the instrumentality carrying the indicia for the contest will retain the match holders or equivalent articles in his possession for a certain period of time, as for instance the week during which the 30 contest is running, even though the matches in the match holder have been used up. Therefore the advertiser gains the benefit of the continuous presence of his advertisement in the possession of the user of the same, or the contestant. 35 Moreover, there is another peculiar advantage derived by the advertiser or by those stores or other places which dispense the article used in the contest, for the advertiser. In other words, persons will be caused, by reason of the carrying 40 on of the contest, to call back at the store, or other place where the articles of the invention are being given out, so as to get additional of these articles since in the carrying out of the contest the articles will have different series of letters or 45 indicia and the more of these letters that are in the possession of the contestant the greater will be the latitude with which he will be able to prepare his jingle or limerick by reason of the enlarged scope of use of words incident to the increased number of letters comprising the indicia carried by the article of manufacture or advertising novelty.

A more full understanding of the details of the construction of my advertising novelty inci- 55

dent primarily to the mode of secreting the indicia applied thereto and the manner in which this indicia is made accessible readily by the peculiar construction and arrangement of the fastening means and enclosing parts will be had upon reference to the accompanying drawing, in which—

Figure 1 is a front view of a match holder showing a preferred embodiment of the invention.

Figure 2 is a view similar to Figure 1 but showing the match holder open or with the front flap of the cover outspread to enable a match to be torn off and used.

Figure 3 is a view similar to Figure 1 but showing the opposite side of the match holder or novelty and illustrating the weakening slots and openings adjacent to the staple enabling the back of the cover to be separated from the match supporting tabs in such a way as to expose the secret indicia.

Figure 4 is a view illustrating the match holder as when the back of the cover is torn away from the stapled match holding tabs and match holding flap exposing the letters or secret indicia useful for the contest purposes of the invention.

Figure 5 is a broken or fragmentary view similar to certain portions of Figure 4, but showing a different selection of letters constituting the hidden indicia.

The detail features of the invention are of extreme simplicity as the invention is embodied in an ordinary paper match holder such as commonly dispensed today, generally without charge, by restaurants, at cigar counters, in hotels, and the like, these match holders being usually supplied by manufacturers or advertisers to be given away, for the advantage of the advertising.

With the above in mind, such a match holder may be described as consisting of a cover including a front flap or member 1, a back or base member 2, the latter having its lower portion folded upon itself to provide a match carrying and scratch flap 3. The matches are paper matches as shown at 4 in the drawing and they are integral with the attaching tabs 5 and slit apart in the customary way. The matches are held in the cover by a staple 6 which passes through the flap 3, the match holding tabs 5, and the lower portion of the back 2 of the cover member. Usually there are two layers of matches 4 and therefore there are two tabs 5.

Now for the contest or competition purposes that have been previously described, I place on the portion of the back 2 of the cover adjacent to the inner edges of the tabs 5, letters comprising indicia 7. These letters as illustrated in Figure 4 will run for certain match holders to be dispensed as consecutive letters of the alphabet from A to Z. In others of the match holders or advertising novelties dispensed, these letters will run say from B to K to provide the indicia 7. This idea may be carried out by using any series of different selections of letters to provide the indicia 7, the idea being to employ different series of letters in order that the contestant in the competition may desire to call back at the same store or place dispensing the articles several times, having in view that he will possibly receive additional of the novelties carrying additional series of letters because the more letters he has to work with for his jingle or limerick, the greater latitude he will have in wording the latter. Or, in carrying out the invention, a certain store or similar place may have match holders with one series of letters for the indicia 7 and other stores may have match holders with other and different series of letters, compelling the person entering the contest preferably to go to different stores to get as many of the different match holders carrying the indicia 7 as he may desire or require for writing his jingle or limerick.

The element of mystery in the use of the invention is promoted by causing the indicia 7 to be applied to the back 2 of the cover so that it is not visible when the contestant receives the article 10 of manufacture, because the indicia is located in that portion of the back 2 which is clamped closed, so to speak, by the staple 6.

Now to facilitate access to the indicia 7 I provide the back 2 with a slot or slit 8 at one side of the staple 6, and with perforations 10 at the portion directly beneath the staple 6. By providing the slit 8 and the perforations 10, I establish a weakened area designated 11 in Figure 4, of the back 2, which area or section may be readily torn out of said back when the back is pulled away from the tabs 5 to which it is clamped by the staple 6. Of course, when the weakened section or area 11 is thus torn away it leaves an opening 12 in the back 2 and exposes to view all of the characters of the indicia 7 making them conveniently accessible to the person who receives the article of manufacture or advertising novelty and proposes to avail of the indicia 7 in entering the contest in which the article is to be employed. 30 Of course, in this contest there will be offered prizes of stipulated amounts to be dispensed at the end of a week or month or any suitable predetermined period of time, and the rules of the contest will require that the ruptured covers or match holders exposing the letters used by the contestant in the words of his jingle be returned at the time the contestant sends in his jingle or limerick, for enabling the award of prizes for the best ones.

Were it not for the peculiar formation of the weakened section or area 11 by the provision of the slit 8 and perforations 10 or equivalent provisions, when the back 2 is torn away from the tabs 5 carrying the matches 4 or the stubs of these matches, the staple 6 would tend to hold securely a portion of the back 2 beneath the staple and this portion would be retained on the tabs and carry with it certain of the intermediate letters of the indicia 7 so that these letters could not be seen without further mutilation of the back 2, and indeed by such mutilation the letters might themselves be mutilated and rendered invisible.

Of course it is to be understood that suitable advertising may be carried in the advertising space designated 13 in Figures 1 and 3. If found desirable, suitable instruction slips may be handed to the persons to whom the match holders are dispensed in order to advise them of the rules of competition, or, under some conditions, these rules may be printed directly upon the match holders or advertising novelties.

Obviously, some persons will not be able to write a jingle or limerick with only the letters supplied by the indicia 7 of one of the match holders they receive. They require some additional letters in order to get the necessary words of their jingle in and to authorize the use of some additional letters for their jingles. Under these conditions such persons may call back at the different dispensing places for the match holders several times until they get a sufficient number of letters as will enable them to enter their jingle as written in the particular contest. The dis- 75 tributors of the match holders will preferably operate under a rule to supply only one match holder to a person each time he calls, and other similar rules to establish fairness of the contest to which my novelty is employed. My advertising novelty comprises obviously a dispensing package having useful removable elements such as matches 4 secured therein, and folded so as to hide the useful indicia from normal view, the stapling or fastening means maintaining the said indicia hidden but engaging a weakened section of the cover so as to enable this section to be ruptured or broken away from the cover readily to expose the said indicia after the article has been dispensed.

Having thus described my invention, what I claim as new and desire to secure by Letters Patent of the United States, is—

1. In an advertising novelty of the class described, in combination, a dispensing package comprising a cover, removable elements carried by said cover, indicia applied to the cover, and fastening means securing the said removable elements to the cover in such a way as to cause the cover to overlap the indicia and hide the same from view in the normal condition of the package, said removable elements comprising tabs attached to the cover by said fastening means, and the fastening means comprising a staple passing through the cover and the said tabs, the area of the cover adjacent to the tabs being weakened in its connection to the cover so that when the cover is pulled away from the staple the weakened section adjacent to the staple will be separated from the cover to afford the exposure of the indicia aforesaid.

2. A match dispensing package comprising a cover including a back, and a front flap, said cover having a match tab securing flap extending from the back and folded thereon, removable elements comprising matches and match tabs carrying said matches, the match tabs received between said match holding flap and the back of the cover, a staple passing through the match tabs, the cover, and said flap, and indicia located adjacent to the point at which the said flap is folded to fold upon the cover and said match tabs, said indicia normally being hidden in the dispensing condition of the package with the cover stapled to the match holding tabs, and said cover being separable from the match tabs in order to expose said indicia, the back of the cover adjacent to the portion fastened by the staple being provided with a weakening slit adjacent to said staple and with perforations beneath the staple establishing a weakened area or section so that when the back of the cover is pulled away from the tabs holding the matches, said weakened area or section will be separated from the back of the cover to thereby fully expose the indicia applied in the manner stated.

HERBERT H. CAMERON. 30